The ornamental design for the stackable tray for holding cartridges, as shown and described herein.

DESCRIPTION

FIG. 1 is a top isometric view of the stackable tray for holding cartridges;

FIG. 2 is a bottom isometric view thereof;

FIG. 3 is an alternative bottom isometric view thereof;

FIG. 4 is a top plan view thereof;

FIG. 5 is a bottom plan view thereof;

FIG. 6 is a front side view thereof;

FIG. 7 is a rear side view thereof;

FIG. 8 is a left side view thereof; and,

FIG. 9 is a right side thereof.
